UNITED STATES PATENT OFFICE

HENRY GLIEDEN, OF BROOTEN, MINNESOTA

FLUE STOPPER

Application filed May 28, 1929. Serial No. 366,716.

This invention relates to flue stoppers employed for closing stove pipe openings of chimneys, the primary object of the invention being to provide a device of this character which will insure a close fit so that smoke and soot cannot pass into the room.

An important object of the invention is to provide a device of this character including an inner section constructed of sheet metal to receive one end of the stove pipe extended into the chimney opening, the inner section being constructed to provide a support for the flue stopper proper used in closing the stove pipe opening when the stove pipe has been removed.

A further object of the invention is to provide a flue stopper constructed of concrete or similar material, the thimble having a shoulder to engage the inner section so that the outer surface of the flue stopper will lie flush with the wall surface to the end that the flue stopper will be invisible when covered with wall paper or paint in finishing the room.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a chimney flue stopper, constructed in accordance with the invention.

Figure 2 is a plan view thereof.

Figure 3 is a vertical sectional view through the flue stopper showing the flue stopper as positioned in a stove pipe opening.

Referring to the drawing in detail, the reference character 5 designates a chimney wall which has the usual stove pipe opening 6 formed therein for the reception of a stove pipe. The outer section of the flue stopper, is indicated by the reference character 7 and is constructed preferably of concrete, the

same being formed with a flange 8 seated in a recess formed at the mouth of the opening.

The reference character 9 designates an inner tapered tubular section which is provided with a laterally circumferential flange 10 that fits in a recess of the outer section 7 of the flue stopper, locking the tubular section 9 in position.

The flue stopper proper is indicated by the reference character 12 and is formed preferably of concrete material the same being provided with an extension 13 of a length to pass into the section 9 where it will hold the flue stopper 12 in position. A shoulder indicated at 14 is provided adjacent to the outer end of the flue stopper and contacts with the inner end of the section 9 to restrict inward movement of the flue stopper and insure the flue stopper being properly positioned to the end that the outer surface of the flue stopper will lie flush with the wall surface so that when the wall is finished as by papering or painting, the stove pipe flue stopper will be invisible to the eye.

In order that the flue stopper may be readily removed, a depression 15 is formed centrally of the flue stopper, defining a rib 16 to be grasped by the fingers so that the flue stopper may be readily handled.

From the foregoing it will be obvious that due to this construction, a flue stopper is provided which is exceptionally strong and durable, and one which will lend the appearance of the solid wall, when positioned in a stove pipe opening of a chimney.

I claim:

1. A flue stopper comprising an inner tapered tubular member to be secured within a chimney opening, a removable body portion, an extension forming a part of the body portion, said extension being of a diameter to fit within the tubular member to secure the body portion in position, and said tubular member adapted to grip the extension.

2. A flue stopper comprising an outer section to be fitted in a flue opening, a tubular member formed of sheet metal material secured to the outer section and extended inwardly therefrom, a body portion of a diameter to fit within the outer section, an exten-

sion forming a part of the body portion and adapted to fit within the inner tubular member, and said inner tubular member adapted to grip the body portion to hold it in the outer member.

3. A flue stopper comprising an inner tubular member to be secured within a chimney opening, a removable body portion having a reduced portion defining an annular shoulder, the reduced portion adapted to extend into the tubular member to be secured in the chimney opening by the tubular member, and the end of the tubular member adapted to engage the shoulder to restrict movement of the body portion within the chimney opening.

In testimony that I claim the foregoing as my own, I have hereto affixed my signature.

HENRY GLIEDEN.
